INVENTOR

BY Victor J. Evans

WITNESS: John Donoran

ATTORNEY

UNITED STATES PATENT OFFICE

DELMER H. MOORE, OF GREENVILLE, MICHIGAN, ASSIGNOR TO MOORE PLOW AND IMPLEMENT COMPANY, OF GREENVILLE, MICHIGAN, A CORPORATION OF MICHIGAN

PLOWSHARE

Application filed February 24, 1928. Serial No. 256,721.

This invention relates to a plow share, the general object of the invention being to form the lower edge of the share and its point with teeth so that it can readily cut through roots and the like and also to provide both faces of the lower part of the share and point with grooves which extend rearwardly at an acute angle to provide a draft and also to harden the rear face of the grooved portion so that the share will be self-sharpening.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the improved share.

Figure 2 is a view of the rear or inner side of the share.

Figure 3 is an end view looking toward the point.

Figure 4 is a section on line 4—4 of Figure 2.

Figure 5 is a section on line 5—5 of Figure 2.

In these views, 1 indicates the share which is formed with the usual point 2. The lower parts of the share and point are thickened on the rear faces, as shown at 3, and the thickened part is chilled so that it is harder than the front lower part of the share. The lower edges of the share and point are formed with saw-like teeth 4 and the front and rear of the lower portions of the share and point are also provided with parallel grooves 5 which slope upwardly and rearwardly, the grooves in the front being oppo-

site those in the rear. These grooves are so formed that the rear walls are much flatter than the front walls and each groove terminates at the front end of each tooth. Thus each tooth is of wedge shape in cross section with the narrow edge of the tooth facing toward the landside.

Thus I have provided a share which has great efficiency in cutting roots and the like and it will pass through the soil with the minimum effort. The share is also self-sharpening, due to the greater wear coming on the front face of the share which also acts to force the plow into the ground and the front face also wears quicker than the rear face, due to the fact that the rear face is chilled or hardened while the front face is comparatively soft. The share is especially designed for plowing alfalfa, sweet clover and other plants which have large fibrous roots.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:—

1. A self-sharpening plow share having its edge formed with a plurality of saw teeth, with grooves in both faces of the lower part of the share, said grooves being parallel and sloping upwardly and rearwardly, each groove having a vertical front wall and an outwardly and rearwardly extending rear wall, with the vertical walls of the top grooves being in alignment with the vertical walls of the bottom grooves and said vertical walls terminating at the front end of each tooth whereby each tooth is of wedge shape in cross section toward the landside and the bottom face of the toothed section being hardened.

2. A plow share having its edge stepped and grooved to provide a plurality of teeth of wedge shape in cross section with the narrow edge of each tooth facing toward the landside, said teeth sloping upwardly and rearwardly.

3. A plow share having its edge stepped and grooved to provide a plurality of teeth of wedge shape in cross section with the narrow edge of each tooth facing toward the landside, said teeth sloping upwardly and rearwardly, the lower part of the teeth being hardened and the upper face of the teeth of softer metal.

15 In testimony whereof I affix my signature.
DELMER H. MOORE.
